UNITED STATES PATENT OFFICE.

STEPHEN KUZMIAK, OF OAKLAND, RHODE ISLAND.

DESIGN FOR A HATCHET.

49,666.

Specification for Design. Patented Sept. 19, 1916.

Application filed August 3, 1916. Serial No. 113,025. Term of patent 7 years.

To all whom it may concern:

Be it known that I, STEPHEN KUZMIAK, a citizen of the United States of America, residing at Oakland, in the county of Providence and State of Rhode Island, have invented a new, original, and ornamental Design for a Hatchet, of which the following is a specification, reference being had to the accompanying drawing, forming part thereof.

In the drawing: Figure 1 is a side eleva-

tion of a hatchet showing my new design. Fig. 2 is a rear elevation thereof, and, Fig. 3 is an end elevation.

I claim:

The ornamental design for a hatchet, as shown.

STEPHEN KUZMIAK.

Witnesses:

ANDREW ADANUSKA,

MARY A. KUZMIAK.
